LOUIS ROCKE, OF BROOKLYN, NEW YORK

SEPARABLE FASTENING DEVICE

Application filed April 21, 1928. Serial No. 271,764.

This invention relates to separable fastening devices of the type wherein a plurality of metallic fastening members are secured upon the edge of a flexible member, as for example the edge of a garment, and are caused to be brought into interlocking engagement by the action of a slider which, when slid longitudinally of the edge of the material in one direction, effects the locking of the members and, when slid in the opposite direction, causes the members to be unlocked.

The principal object of the present invention is to improve upon devices of the above character, by so constructing the fastening members that they will move, under the influence of the slider, more readily into engagement.

A further object is to increase the strength of the fastening members while at the same time avoiding any undue increase in the weight of the parts.

Another object is to so construct the fastening members that they will have no exposed sharp edges, such as could catch in or tear the garment or cut the fingers of the operator.

A further object is to improve upon and simplify the construction of the slider so that it will not only function more efficiently but in addition the manufacturing cost thereof will be decreased.

Another object is to construct the fastening members as male and female parts, the latter being provided with a through aperture, extending in parallelism with the longitudinal axis of the flexible member and serving to engage the two adjacent male members, and said aperture of the terminal female member also serving to co-operate with a hook-shaped male member to permit the complete separation of the two edges of a garment and the re-engagement in proper operative relationship of the parts which form the end members of the series of fasteners, said re-engagement being automatically effected by the mere insertion of the hook-shaped member longitudinally into the slider.

The above and other objects will appear more fully from the following more detailed

description and by reference to the accompanying drawings forming a part hereof wherein Fig. 1 is a side elevation of a satisfactory constructional example of a separable fastening device embodying the principles of my invention; Fig. 2 is a central vertical section through the slider taken substantially on the line 2—2 of Fig. 1; Fig. 3 is a section on the line 3—3 of Fig. 1; Fig. 4 is an enlarged side elevation partly in section showing the manner in which the fastening members move in and out of locked engagement; Figs. 5 and 6 are plan views of a female and a male fastening member respectively; Fig. 7 is a section on the line 7—7 of Fig. 4 and Fig. 8 is a development of the metal blank from which the slider is constructed.

As shown in the drawings a pair of stringers 10 and 11 in the form of fabric tapes are provided along one longitudinal edge with a beaded portion 12 about which the fastening members are securely clamped. Although any suitable expedient may be employed for making the beaded portion 12, such for example as binding or turning the edge of the tape around a small cord or thread of the proper diameter, I prefer to employ a tape in which the beaded edge is formed by cording the edge thereof in the weaving, thus not only eliminating the extra sewing machine operation required when the edge is bound or turned but also providing a much stronger construction.

Secured at spaced intervals along the beaded edge of the stringer 10 is a plurality of male fastening members 13 each of which comprises a reduced preferably cylindrical shank portion 13^a terminating at its inner end in a pair of gripping jaws 13^b adapted to be bent into clamped engagement with said beaded edge to secure said members permanently to the stringer. At its outer end the shank portion 13^a terminates in a ball portion 13^c the top and bottom parts of which form protuberances extending laterally from said shank portion.

The stringer 11 has secured to it at spaced intervals, a plurality of female fastening members 14 each of which also has a central, preferably substantially cylindrical, shank 10^a

portion 14^a the inner end of which also terminates in a pair of gripping jaws 14^b similar to the jaws 13^b. Each of the jaws 13^b and 14^b at its inner end is provided with a small pointed hooked end 15 adapted to penetrate the mesh of the tape and interlock with the threads thereof. The outer end of the shank portion of each of the female members 14 merges and terminates in a flattened head 14^c which is provided with a through aperture 14^d into the opposite ends of which the ball portions 13^e of an adjacent pair of the male members 13 are adapted to be seated.

The outer surface of each flattened head 14^c as shown in the drawings is preferably curved or rounded as indicated by the reference character 14^e.

In accordance with the usual construction of devices of the character to which this invention relates, a slider 25 is provided for causing the beaded edges of the stringers to be bent or curved backwardly to spread the outer ends of the fastening members apart thus permitting co-operating members to be moved into and out of engagement. The slider 25 shown in the accompanying drawings is preferably stamped out of a single piece of sheet metal to form similarly shaped parallel back and front portions 25^a, 25^b which are joined at the upper edges by a bridge 26. A pair of tabs 27 extend from the sides of the bridge 26 and each tab terminates in a pair of lateral projections 28 adapted, when said tabs are bent to the position shown in Fig. 1, to be brought into alignment with the apertures 29, 30 formed in the back and front portions 25^a, 25^b respectively. After the tabs 27 have been bent to their proper position, the front and back portions 25^a, 25^b are bent over into parallelism with each other as indicated in Fig. 2 and until the lateral projections 28 of the tabs extend through the apertures 29, 30. The ends of the projections are then riveted over, thus serving to hold the slider securely in its final condition as shown in Fig. 2. Each of the back and front portions 25^a, 25^b is provided with an inwardly turned flange 31 so that when the slider is bent into its final form 50 the flanges 31 form side walls, which terminate at the top of said slider to provide a pair of top openings 32 which communicate with the slots 33 formed between the edges of the flanges and which extend longitudinally of said side walls. The beaded edges of the stringers with the fastening members secured thereto are adapted to pass through the openings 32 and the flat part of the stringer tapes through the slots 33.

60 In order to provide a convenient means for manipulating the slider the front portion 25^a thereof is struck out to form an elongated bar 34 spaced laterally from the front wall of the slider. This bar serves as a retaining member for a ring 35 or the like which is

passed through the space between said bar and said front wall.

Separable fastening devices of the type to which the present invention relates, as heretofore constructed, have been characterized by the fact that it was necessary to maintain the ends of the tapes at one end thereof permanently secured together in order to keep the fasteners in proper position relatively to each other so that when the stringer was slid longitudinally the co-operating fastening elements would pass readily into locking engagement. Because of this necessity for keeping the ends of the tape in permanently secured relationship, the practical applications of fasteners of this type have been limited unless some special opening and closing device was provided at the ends of the tapes. In accordance with the principles of the present invention I employ a slightly modified construction for the terminal member of the series of male fasteners at one end of the tape 10. This terminal member as shown in Fig. 4 of the drawings and indicated by the reference character 36, has a pair of gripping jaws somewhat similar to the jaws 13^b, and 14^b, except that instead of the outer faces of said jaws being of curved configuration said outer faces are flat and extend at an inclination to the side edges of the tape to provide a wedge-shape as clearly indicated in Fig. 7 of the drawings. At its lowermost end the member 36 is provided with a pair of laterally projecting stops 37 which serve to limit the movement of the slider and prevent it from being disengaged from the tape 10. The part of the member 36 which performs the fastening function is in the form of a hook 38 adapted to pass into through holes 14^d of the terminal female member 14. As shown in Fig. 4 in order to provide a sufficient space between the lowermost male member 13 and the terminal member 36 two female members 14 are placed upon the end of the tape 11 in contacting engagement with each other instead of being spaced from each other as are the other elements 14 upon the tape 11. The space between the lowermost member 13 and the terminal member 36 is such that when the slider 25 is moved to the end of the tape to cause the fastening members to be disengaged, the member 14 just referred to will be turned upwardly and backwardly a sufficient distance to bring it out of engagement with the upper one of the two terminal female members 14.

By providing the member 36 with the inclined side walls shown in Fig. 7 so as to provide a wedge-shaped structure, said member acts as a lock to hold the slider in its terminal position, the inner faces of the front and back portions 25^a, 25^b of the slider engaging the outer inclined faces of the wedge-shaped member 36 with a resilient frictional pressure

that holds the slider against accidental displacement from its terminal position.

The manner in which the device is assembled, as will be readily understood, is as follows: The fastening members 13 and 14 as originally constructed have their gripping jaw portion 13^b and 14^b spaced or spread apart a sufficient distance to permit said jaws to be readily placed over the beaded edges of the stringers. The members of each set of fastening elements are equally spaced along their respective stringers, the spacing between each pair of similar fastening elements being such that when the elements are in locked engagement with their co-operating members, as shown at the lower part of Figs. 1 and 4, the ball-shaped ends 13^c of the male members will project into the holes 14^d of the female members a sufficient distance to positively prevent accidental displacement or unlocking of the elements. The spacing between the members is also such that when the slider 25 is slid longitudinally to accomplish the disengagement or unlocking of the elements, a sufficient opening is formed by the backward bending or turning of the tapes as indicated at the upper part of Fig. 4 to permit the fastening elements to clear one another as they are passing out of locked engagement.

The operation is substantially the same as the usual operation of devices of this kind. The fastening members are caused to be moved into interlocked engagement by sliding the slider longitudinally of the stringers; as shown in the drawings, movement of the slider upwardly causes the fastening members to be engaged and movement downwardly causes them to be disengaged. As the slider moves upwardly, the edge of the stringer is caused to be flexed or curved so that the upper portions of both stringers closely adjacent to, and in the upper part of, the slider diverge in such a manner that the spaces between the outer ends or head portions of each adjacent pair of fastening members is increased. While each adjacent pair of fasteners is spread, as it were, the co-operating male and female members are slipped into engagement by the pressure of the inturned flanges 31 at the lower, smaller end of the slider. The flanges at the lower end of the slider extend in parallelism and are spaced apart a distance substantially equal to the combined width of a co-operating male and female member when the interlocking parts of such members are in engagement. It will be readily understood that as these members are caused to be engaged by the action of the slider, the spherical or ball shaped portions 13^a of the male members 13 will enter into the holes 14^d of the female members 14, the two laterally upwardly and downwardly protruding portions of each ball 13^a engaging with the holes 14^d of an adjacent pair of female members 14. Each

female member in turn has its hole 14^d in engagement with an adjacent pair of male members on the opposite stringer.

The curved outer surface 14^e of the flattened head 14^c of each female member and also the curved outer end of each ball portion 13^a tend to facilitate the slipping into engagement of the co-operating members. Due to this curvature of each of the members and the general configuration of the flattened head 14^c, all sharp edges on the protruding parts of the fastening member are avoided.

After the fasteners have been actuated into interlocked engagement the holding action of each co-operating pair of members prevents disengagement of the members immediately below them so that accidental disengagement of the parts is absolutely prevented. When it is desired to disengage or unlock the fasteners, the slider 25 is slid downwardly in

the well known way, the bridge 26 and tabs 27 at the upper part of the slider functioning to spread the pair of stringers with their respective sets of fastening members apart and to flex the same in such a manner that the fastening members will readily slip out of engagement. When the slider 25 has been slid to the full limit of its travel in performing the unlocking function and is engaged with the wedge-shaped member 36 the lowermost

male member 13 will then be swung upwardly and backwardly a sufficient distance to permit the tape 11 with its fastening elements to be slid longitudinally out of the left hand top opening of the slider, thus permitting the two tapes 10 and 11 to be completely disengaged from each other. If these tapes are assumed to be secured to a garment, such for example as a vest, it will be obvious that such garment can be put on or taken off a wearer in the usual manner and that it will not have to be slipped over the head like a sweater or jersey. The stops 37 co-operate with the wedge-shaped member 36 to positively hold the slider in its proper position in order that the operation of re-engaging the fastening members can be readily accomplished.

The placing of the series of members again into proper position or engagement to be locked again by the longitudinal sliding of the slider 25 will be readily understood. As has been above pointed out, the slider is held against movement by the member 36, the lowermost end of the tape 11 is passed into the left side top opening of the slider until the holes of the two contacting female members 14 at the end of the tape 11 pass into engagement with the hook 38. The horizontally extending part of the hook serving to limit the inward movement of the tape 11 and hold the female fastening members carried thereby in their proper position relatively to the male fastening members. The slider 25 can then be slid upwardly to cause the parts to move into locking engagement.

When the hook 38 has been inserted into the holes of the two contacting female members 14 at the end of the tape 11, and the slider 25 has been moved upwardly to lock the parts, 5 the terminal end of the hook abuts against the ball portion of the lowermost male member 13, thus causing the two lowermost female members to be gripped tightly between the hook and said male member.

10 As has been hereinbefore pointed out, both the male and the female members are rounded on their outer ends so that there is a total absence of any sharp edges that would tend to catch in, or tear an undergarment of the 15 wearer or would tend to cut or scratch the person of the wearer. The ball shaped construction of the male members and the manner in which said portions engage with a circumferential contact with the female 20 members permits a substantially universal flexure of the fastening elements after they have been locked in engagement, thus permitting a garment provided with the fasteners of my invention to adjust itself readily 25 to irregular shapes or contours.

It will be understood that many changes, variations and modifications may be resorted to without departing from the principles of my invention.

30 I claim:

1. A slider for a separable fastening device of the type wherein two sets of metallic fastening members secured to the edges of the two pieces of flexible material are moved into 35 and out of interlocked engagement by the action of said slider, characterized by the slider being made of a single piece of sheet metal formed to provide a front portion and a back portion, each of which is provided with in-turned flanges forming slotted side walls for 40 said slider, a bridge portion joining said front and back portions at the top thereof and a pair of tabs each having a pair of reduced lateral extensions extending from said 45 bridge portion, said front and back portions being provided with a pair of axially aligned apertures, and the reduced ends of said tabs being inserted into said apertures and being 50 riveted over to hold said portions in spaced relationship.

2. A separable fastening device comprising two sets of metallic fastening members, each set of said members being secured upon the 55 edge of a flexible material in spaced relationship and being different from the other set, one set comprising male members and the other set female members, the latter being provided with a hole extending parallel to the 60 edge of the material to which they are fastened, characterized by the provision of two female members located in contacting engagement adjacent to one end of the edge of said material, and a hook shaped terminal member 65 located at the corresponding end of the

male set of members for engagement with the holes of said two female members.

3. A separable fastening device comprising two sets of metallic fastening members, each set of said members being secured upon the 70 edge of a flexible material in spaced relationship and being different from the other set, one set comprising male members and the other set female members, the latter being provided with a hole extending parallel to the 75 edge of the material to which they are fastened, characterized by said male members each being provided with a ball shaped portion which engages within the holes of two adjacent female members, two female members located in contacting engagement adjacent to one end of the edge of said material, and a hook shaped terminal member located at the corresponding end of the male set of 80 members for engagement with the holes of said two female members, said hook extending through the holes of said two female members and abutting at its terminal end with the ball of the terminal male member.

In testimony whereof I have hereunto set 90 my hand.

LOUIS ROCKE.
